UNITED STATES PATENT OFFICE.

JOSEPH B. HOLDEN, OF SYRACUSE, NEW YORK, ASSIGNOR TO REMINGTON TYPE-WRITER COMPANY, OF ILION, NEW YORK, A CORPORATION OF NEW YORK.

TYPEWRITING MACHINE.

1,424,409.

Specification of Letters Patent. Patented Aug. 1, 1922.

Application filed January 25, 1922. Serial No. 531,649.

To all whom it may concern:

Be it known that I, JOSEPH B. HOLDEN, citizen of the United States, and resident of Syracuse, in the county of Onondaga and 5 State of New York, have invented certain new and useful Improvements in Typewriting Machines, of which the following is a specification.

My invention relates to typewriting and 10 like machines, and more particularly to the mounting and guiding parts of the type actions of such machines.

The present invention was devised more 15 particularly for embodiment in the Remington Portable machine, and is intended to improve certain features thereof disclosed for example in the patents to John H. Barr, No. 1,320,084, dated Oct. 28, 1919, and to Arthur W. Smith, No. 1,342,513, dated June 20 8, 1920, and to overcome certain disadvantages found in the features in question.

To the above and other ends which will hereinafter appear, my invention consists in the features of construction, arrangements 25 of parts and combinations of devices set forth in the accompanying description and particularly pointed out in the appended claims.

In the drawings, wherein like reference 30 characters indicate corresponding parts in the different views,

Figure 1 is a detail fragmentary transverse sectional view of a portion of the machine showing the combined guide comb and 35 fulcrum together with some of the associated parts, the section being taken on the line 1—1 of Fig. 4 and looking in the direction of the arrow at said line.

Figure 2 is an enlarged detail transverse 40 sectional view of the same taken on the line 2—2 of Fig. 1 and looking in the direction of the arrow at said line.

Figure 3 is a like sectional view of the 45 same taken on the line 3—3 of Fig. 1 and looking in the direction of the arrow at said line.

Figure 4 is a detail fragmentary vertical 50 fore-and-aft sectional view of the machine taken on the line 4—4 of Fig. 1 and looking in the direction of the arrow at said line.

Figure 5 is an enlarged detail fragmentary perspective view showing the centrally disposed interlocking means whereby the 55 guide comb and keeper plate are firmly though detachably connected.

While I contemplate, in the present instance, embodying my invention in a light portable typewriting machine such as the Remington-Portable, it should be understood that the invention is available for use, 60 and may be embodied in other styles of machines.

I have shown only so much of the Remington-Portable machine as may be necessary to arrive at an understanding of my 65 invention in its inclusion therein.

It is desirable in a portable machine to make the parts as light and compact as possible consistent with the necessary rigidity and strength required therefor. When it is 70 feasible to use sheet metal from which to construct parts of the machine, such course is deemed desirable, both from the point of view of lightness of construction and reduction in cost of manufacture. 75

In the present instance all of the parts shown, including the frame, key levers, sub-levers, type bars, guide comb for the key levers and the mounting and guide for the sublevers are made of sheet metal. 80

The main object of my present invention is to so construct and unite certain of these parts that they shall, in their support one by another, have sufficient rigidity to prevent them from flexing or being sprung apart and thereby prevent other parts from being accidentally disarranged or displaced during the 85 operation of the machine, as will hereinafter more clearly appear.

The machine comprises an outer sheet 90 metal frame 1 and an inner sheet metal frame 2 detachably secured thereto and supporting various working parts of the machine. The forward ends of the side plates of the inner supporting frame 2 are united 95 by a sheet metal combined fulcrum plate and guide comb, indicated as a whole by the reference numeral 3. Inwardly projecting ears 4 are formed on the side plates of the frame 2 and are tapped to receive headed 100 screws 5 and 6 which connect the member 3 to said frame. The lower portion of the member 3 is slotted at 7 from its lower edge to receive key levers 8 and form a guide comb therefor. Above the slots 7, and extending longitudinally of the member 3, is 105 formed a rib 9 that tends to strengthen the member against lateral deflection or bending. Guide slots 10 are formed in the member 3 above the rib 9 and extend down from 110

the upper edge thereof. Such slots are aligned with the slot 7 so that each slot 7 has a companion slot 10 immediately above it. Key actuated devices or sublevers 11 are received at their forward ends in the slots 10 and are maintained spaced apart by and are fulcrumed on the member 3. In the present instance these sublevers are made of sheet metal, each being formed with a substantially V-shaped notch 12 therein. The walls of the notch 12 in each sublever, at and near the point of intersection thereof, form a bearing or seat 13. Each sublever is detachably supported as by a fulcrum, on the bottom wall 14 of the associate slot 10 in the member 3, as shown. The upper forward edge portion of each sublever 11 is curved at 14^a in an arc around the bearing 13 of the sublever. This enables the sublever to oscillate freely on its fulcrum while the sublever by co-operation with a keeper, as will hereinafter appear, is prevented from being displaced from its fulcrum.

In order to prevent the sublevers from being accidentally displaced from their fulcrums I provide a so-called separately detachable keeper 15. This keeper is preferably made of sheet metal and is substantially angular in cross section to give added rigidity thereto. The member 15 extends transversely of the machine above the member 3 and is provided with downwardly bent ears 16 at the ends thereof. These ears are apertured to receive the stems of the screws 6 which, with the screws 5, secure the member 3 to the machine frame.

In this manner the members 3 and 15 are rigidly though detachably connected together at the ends thereof and also are secured to the frame of the machine. The part 15^a of the keeper is preferably curved in cross section to conform substantially to the curvature of the edges 14^a of the sublevers 11 situated directly beneath said part 15^a. There is preferably, in the normal position of the parts, a bare clearance between each edge 14^a and the part 15^a of the keeper, so that any upward displacement of the forward end of a sublever from its fulcrum brings the edge 14^a of the sublever against the keeper and prevents any further movement of the bearing of the sublever away from its fulcrum.

In order that the keeper plate 15 and the combined comb and fulcrum plate 3 may be prevented from being sprung or flexed relatively one to the other, which might result in the sublevers, or some of them, being displaced or disarranged, I provide by my present invention means for firmly though detachably connecting the members 3 and 15 together intermediate the ends thereof, as well as at the ends.

I prefer to provide at various points throughout the length of the member 3 up-

wardly projecting integral connecting lugs 17 that extend through openings in the part 15^a, each opening conforming in shape to the cross section of a lug received therein, so as to prevent any relative movement between the members 3 and 15 fore-and-aft of the machine or from side to side thereof. A centrally disposed integral lug 18 on the member 3 projects through a central opening 19 in the part 15^a of the keeper plate. This opening is of a width that corresponds to the width of the lug 18 but is deeper fore-and-aft of the machine than the thickness of said lug. A substantially T-shaped connecting head, designated as a whole by the reference numeral 20, has a depending stem 21 that passes through the opening 19 from above and is tapped to receive a headed screw 22. The stem of the latter passes from front to rear through an opening 23 in the member 3 and is then threaded into the tapped opening in the head 20, firmly though detachably connecting said head to the member 3. The depending stem 21 is of a width corresponding to the width of the opening 19, and is of a thickness which, with the thickness of the lug 18, fills the depth of the opening 19 fore-and-aft of the machine. When the member 20 is secured in place the cross head or piece 24 thereof, which is of a length that exceeds the width of the opening 19, overlaps and rests on the body portion of the part 15^a of the keeper. This detachable interlocking connection between the member 3 and the keeper 15, about midway in the length thereof, positively and effectively ties the two together intermediate their ends so that there can be no movement of one relatively to the other in any direction. The comparatively rigid keeper being thus firmly connected to the member 3 prevents the latter from being flexed or sprung, which springing of the plate 3 would result in a displacement or disengagement of the sublevers 11. The employment of the lugs 17 in the manner described at various points throughout the length of the members 3 and 15, and the screws 6 at the end of said members, further aid in effectively and firmly, though detachably, connecting them together and preventing one part from being sprung or moved relatively to the other when in use at all points lengthwise of said members. The means in question nevertheless enable the keeper 15 to be readily detached from the member 3 when desired, thus enabling a detachment of the sublevers from said member to be readily effected.

For the purposes of my present invention it is immaterial how the key levers 8 are connected to actuate the sublevers 11 and how the latter are connected to actuate the type bars. In the present instance said parts are shown connected as they are in the Remington-Portable machine, and as disclosed in

the patents hereinbefore referred to. Thus each key lever 8 is connected by a link 25 to its sublever 11, the latter being connected by a second link 26 to a second sublever 27. 5 Each sublever 27 is fulcrumed intermediate its ends at 28, and is provided at its rear end with segmentally arranged gear teeth 29. These teeth mesh with similar teeth 30 on the heel of the companion type bar 31, pivoted at 32 to strike downwardly and rearwardly against the top of a platen, not shown.

From the foregoing description it will be understood that I have provided simple, inexpensive and effective means for detachably securing the combined comb and fulcrum plate 3 and the keeper 15 together, and for supporting one by the other to prevent them from being accidentally sprung 20 apart, and thereby prevent the sublevers 11 from being accidentally disarranged or getting out of place.

Various changes may be made without departing from my invention.

25 What I claim as new and desire to secure by Letters Patent, is:—

1. In a typewriting or like machine, the combination of key controlled levers, a fulcrum member on which said levers are fulcrumed and detachably mounted, a separately detachable keeper plate co-operative with said levers to prevent their detachment from the fulcrum member, and means substantially mid-way in the length of said 35 keeper plate for rigidly though detachably connecting it to said fulcrum member.

2. In a typewriting or like machine, the combination of key controlled levers, a combined fulcrum and guide comb member on 40 which said levers are fulcrumed and detachably mounted and by which they are maintained spaced apart, a detachable sheet metal keeper plate co-operative with said levers to prevent their detachment from said fulcrum member, and interlocking means intermediate the ends of said keeper plate for firmly though detachably connecting it to said combined fulcrum and guide comb member to prevent a relative movement 45 between the latter and said keeper plate during the use of the machine.

3. In a typewriting or like machine, the combination of key controlled levers, a fulcrum member on which said levers are fulcrumed and detachably mounted, a separately detachable keeper plate co-operative with said levers to prevent their detachment from the fulcrum member, and means for rigidly though detachably connecting said 55 keeper plate to said fulcrum member, said means comprising a substantially T-shaped head the stem of which passes through an opening in the keeper plate, and means for detachably connecting the stem of said head 60 to the fulcrum member.

4. In a typewriting or like machine, the combination of key controller levers, a combined fulcrum and guide comb member on which said levers are fulcrumed and detachably mounted and by which they are maintained spaced apart, a detachable sheet metal keeper plate co-operative with said levers to prevent their detachment from said fulcrum member, and interlocking means for firmly though detachably connecting said keeper plate and said combined fulcrum and guide comb member to prevent a relative movement between the latter and said keeper plate during the use of the machine, said means comprising a separate sheet metal substantially T-shaped head the stem of which passes through an opening in said keeper plate, and a screw for detachably connecting the stem of said head with said combined fulcrum and guide comb member. 70 75 80 85

5. In a typewriting or like machine, the combination of key controlled levers each formed with a substantially V-shaped notch therein, a slotted sheet metal combined guide comb and fulcrum plate in slots in which 90 said levers are received, each lever being detachably seated at its notched portion on the bottom wall of its guide slot in the comb plate to fulcrum thereon, a keeper plate which extends over the levers and prevents them from being moved off their fulcrum, and means at various points throughout the length of said keeper plate for detachably connecting it to said combined guide comb and fulcrum plate. 95 100

6. In a typewriting or like machine, the combination of key controlled levers each formed with a substantially V-shaped notch therein, a slotted sheet metal combined guide comb and fulcrum plate in slots in which 105 said levers are received, each lever being detachably seated at its notched portion on the bottom wall of its guide slot in the comb plate to fulcrum thereon, a keeper plate which extends over the levers and prevents them from being moved off their fulcrum, and means at various points throughout the length of said keeper plate for detachably connecting it to said combined guide comb and fulcrum plate, said means including a 110 separate substantially T-shaped head the stem of which passes through an opening in said keeper plate, and means for detachably connecting the stem of said head with said combined fulcrum and guide comb member. 115 120

7. In a typewriting or like machine, the combination of key controlled sheet metal levers each formed with a substantially V-shaped notch therein, a slotted sheet metal 125 combined guide comb and fulcrum plate in the slots in which said levers are received, each lever being detachably seated at its notched portion on the bottom wall of its guide slot in the comb plate to fulcrum 130

thereon, a sheet metal keeper plate which extends over the levers and prevents them from being moved off their fulcrum, and means at various points throughout the length of said keeper plate for detachably connecting it to said combined guide comb and fulcrum plate and including substantially centrally located means for preventing relative movement between the keeper plate and guide comb in any direction.

8. In a typewriting or like machine, the combination of key levers, sublevers controlled thereby, a sheet-metal combined fulcrum plate for the sublevers and comb plate for the key levers and sublevers and from which plate the sublevers may be detached, a sheet metal keeper plate for preventing detachment of the sublevers from their fulcrums on said combined plate, and connecting means at different points throughout the length of the keeper plate for firmly though detachably connecting said keeper plate to said combined fulcrum and comb plate.

9. In a typewriting or like machine, the combination of key levers, sublevers controlled thereby, a sheet metal combined fulcrum plate for the sublevers and comb plate for the key levers and sublevers and from which plate the sublevers may be detached, a sheet metal keeper plate for preventing detachment of the sublevers from their fulcrums on said combined plate, and connecting means at different points throughout the length of the keeper plate for firmly though detachably connecting said keeper plate to said combined fulcrum and comb plate, said means including a substantially T-shaped head the stem of which passes through an opening in said keeper plate, and means for detachably connecting the stem of said head to said combined fulcrum and comb plate.

10. In a typewriting or like machine, the combination of key controlled levers, a fulcrum member on which said levers are fulcrumed and detachably mounted, and a separately detachable keeper plate co-operative with said levers to prevent their detachment from the fulcrum member, said keeper plate being apertured at various points throughout its length and said fulcrum member having a series of projections extending there-

from through and fitting said apertures in the keeper plate to detachably connect the plate to the fulcrum member.

11. In a typewriting or like machine, the combination of key controlled levers, a fulcrum member on which said levers are fulcrumed and detachably mounted, a separately detachable keeper plate co-operative with said levers to prevent their detachment from the fulcrum member, said keeper plate being apertured at various points throughout its length and said fulcrum member having a series of projections extending therefrom through and fitting said apertures in the keeper plate to detachably connect the plate to the fulcrum member, a substantially T-shaped connecting head having its stem extending through and fitting one of said apertures, and a screw for detachably connecting the stem of said head to said fulcrum member.

12. In a typewriting or like machine, the combination of key levers, sublevers controlled thereby, a sheet metal combined fulcrum plate for the sublevers and comb plate for the key levers and sublevers and from which plate the sublevers may be detached, a sheet metal keeper plate for preventing a detachment of the sublevers from their fulcrums on said combined plate, and connecting means at different points throughout the length of the keeper plate for firmly though detachably connecting said keeper plate to said combined fulcrum and comb plate, said connecting means comprising projections on said combined fulcrum and comb plate that extend through and fit in openings in the keeper plate, a substantially T-shaped head disposed about mid-way in the length of the keeper plate and the stem of which passes through and fits an opening therein, and a screw for connecting the stem of said head to the combined fulcrum and comb plate.

Signed at Syracuse, in the county of Onondaga and State of New York this 23rd day of January A. D. 1922.

JOSEPH B. HOLDEN.
